Attorney

UNITED STATES PATENT OFFICE.

SAMUEL HEATH, OF PHILADELPHIA, PENNSYLVANIA.

ASH-SIFTER.

1,294,262.

Specification of Letters Patent. Patented Feb. 11, 1919.

Application filed December 13, 1918. Serial No. 268,605.

To all whom it may concern:

Be it known that I, SAMUEL HEATH, a citizen of the United States, residing at Philadelphia, in the county of Philadelphia and State of Pennsylvania, have invented certain new and useful Improvements in Ash-Shifters, of which the following is a specification.

My invention relates to improvements in ash sifters, and the main object of my invention is the provision of a portable ash sifter which can be fitted as a whole to the ash chamber of a stove or furnace, receive the ashes direct from the grate and effect the sifting with ease to separate the cinders from the ashes.

Another object of my invention is the provision of an ash sifter which can be adjusted to fit ash chambers of different sizes to adapt the device for use with stoves and furnaces of different shapes or sizes and which will operate quickly and perfectly under all conditions.

Another object of my invention is the provision of an ash sifter in the form of a box or case to fit the ash chamber and thus permit instant application or removal; which can be quickly operated to sift and separately collect the cinders and ashes and which will absolutely prevent flying or scattering of the dust or ashes.

Another object of my invention is the provision of an ash sifter which will quickly and cleanly separate and collect the cinders and ashes; which will be light in weight, but strong and durable, simple and inexpensive of production and thoroughly efficient and practical.

To attain the desired objects, my invention consists of an ash sifter embodying a box or case adapted to fit the ash chamber of a stove or furnace and composed of a casing, an ash receiver, a sifter or screen and a protecting cover.

The invention also consists of an ash sifter consisting of novel features of construction and combination of parts, substantially as shown, described and claimed herein.

In order that the detailed construction and operation of my ash sifter may be fully understood and its many advantages and features of merit be fully appreciated, I have shown in the accompanying drawings

an ash sifter constructed according to my invention.

Figure 1 is a transverse sectional view of the ash sifter in position for use, the grate and ash pit being shown in dotted lines.

Fig. 2 is a longitudinal sectional view of the ash sifter.

Fig. 3 is a detail view of a slightly modified construction where necessary to have a box or casing of increased width, and

Fig. 4 is a detail view of a further construction of my invention.

The invention as a whole is portable to enable it to be readily applied and removed from the ash pit or chamber, and consists of the pair of side members A, formed with cleats B, to receive the ash drawer or receiver C, the upper of said cleats forming the guide for the shaker or screen D, formed with the grasping portion E, and surmounting the side members A is the sliding cover F.

In use the cover F is first removed and the operation of dumping or shaking begun, the ashes from the grate falling upon the screen D. When this is accomplished the cover F is replaced to prevent scattering of dust, and the screen is reciprocated, which causes the cinders to remain upon the screen and the ashes to fall into the receiver, thus separating the ashes and cinders without removing the device from the ash pit and preventing the scattering of dust.

The side members A may be formed with slots G, to receive the flat strips H formed with slots J, to receive stop pins K, to adjust the width of the case to different sized ash pits, or the side members may be formed with depending feet or supports L to adapt the case to fit ash pits of increased heights, as circumstances require.

The entire article may be made of sheet metal to insure cheapness, lightness and durability, and it will be apparent that the device can be easily applied and removed; can be quickly operated to separate the ashes and cinders without making a dust; that the sifter will not interfere with the operation of the stove or furnace; and from all points of view will prove efficient and practical.

I claim:

1. An ash sifter consisting of a box or case, composed of side members formed with cleats dividing the case into an ash receiver

chamber and a sifter compartment, an ash receiver in the receiver chamber, a sifter in the sifter compartment, and means for adjusting the side members laterally to adapt the case to ash pits of different sizes.

5. An ash sifter consisting of a box or case, composed of side members formed with cleats dividing the case into an ash receiver

chamber and a sifter compartment, an ash receiver in the receiver chamber, a sifter in the sifter compartment, and a cover ¹⁰ mounting the side members, said side members being formed with depending feet to increase the height of the case.

In testimony whereof I affix my signature.

SAMUEL HEATH.
